UNITED STATES PATENT OFFICE

JAMES D. LALOR, OF BALTIMORE, MARYLAND, ASSIGNOR, BY MESNE ASSIGNMENTS,
TO THE FLUID HEAT COMPANY

DEVICE FOR VAPORIZING LIQUIDS

Application filed February 18, 1925. Serial No. 10,048.

This invention is concerned with the atomization of liquids, its main object being to enable perfect reduction to a vaporized consistency of comparatively heavy and dense liquids, more particularly hydro-carbons of the low Baumé varieties such as are ordinarily used in oil burning installations or systems, so as to render them susceptible of ready carburization by subsequent mixing with combustion-supporting air in the proper proportions.

A further object of my invention is to provide a highly efficient, thoroughly reliable device of very simple design and construction by aid of which perfect vaporization of heavy hydro-carbons can be conveniently and economically carried out.

The various advantages accruing to this invention will be readily apparent from the detailed description hereinafter of an atomizer conveniently embodying my novel improvements, the same being shown in the accompanying drawings.

Fig. I is a sectional view of the device.

Fig. II is a fragmentary elevation of a portion of the main casing member of the atomizer.

Fig. III is a face view of a core piece forming a part of the nozzle by which the fluid to be atomized is converted into a jet for interaction with the atomizing medium.

Figs. IV and V are, respectively, a plan view and a side elevation showing the atomizer in association with regulating gauges suitable for controlling the delivery pressure of the liquid to be atomized and the atomizing medium.

Referring first to Fig. I of these illustrations, the atomizer will be observed as comprising an elongated body member 1, and a cylindric shell 2 which encloses the greater portion of the body member, said shell being secured by a thread connection shown at 3, and fixed by a jamb nut 4. Integrally formed at the rear end of the body member 1 are a pair of oppositely-directed laterally-extended nipples 5 and 6 that are threaded for convenience of coupling, as shown in Figs. IV and V, with pipe lines 7 and 8 through

able atomizing medium, such as steam or air under pressure, are respectively conducted to the device. The inner enclosed end of the body member 1 as well as an intermediate portion thereof are reduced in diameter with resultant formation jointly with the shell 2, of annular spaces 9, 10, these spaces communicating by way of a multiplicity of angularly-pitched channels formed, as shown to best advantage in Fig. II, by grooves 11 in the periphery of a circumferential enlargement 12 of the body member 1, setting apart the annular spaces 9, 10 referred to. The latter —10— of these two spaces in turn communicates, by way of a duct 13, directly with the nipple 6 so that a continuous course is established in the device for guiding the atomizing medium delivered through the pipe line 8.

Located in a cavity 14 at the inner or enclosed end of the body member 1 of the atomizer is a core piece 15, which constitutes a part of a nozzle comprehensively indicated by the letter N, and which—although generally cylindric—has a portion 16 thereof somewhat reduced diametrically, with the forward end fashioned to frusto-conical configuration as indicated at 17, and the opposite end circumferentially enlarged as at 18 to a diameter corresponding substantially to that of the cavity 14. A screw tip 19 closing the end of the cavity 14 and constituting another component part of the nozzle N, is characterized by an inward extension with an axial hollow 20 which corresponds in configuration to, and accommodates the core piece 15, a compressible washer 21, (preferably a ring of asbestos or the like encased by soft sheet metal such as copper) being interposed behind said core piece to insure firm pressure contact between the contiguous conical surfaces at 22 in the assembly. A passage 23 beginning at the nipple 5, extends axially through the main body part 1 and is continuous with a registering axial duct 24 in the core piece 15. The lateral or radial branches of this duct 24 lead to an annular space 26 formed within the nozzle N by virtue of the diametrical reduction 16 of the core piece 15. A comparatively small cir-

cular cavity 27 provided by a counter recess in the hollow 20 of the tip 19, is entered by way of a number of tangentially-disposed channels 28 in the sloping surface of the core piece 14, see Fig. III, which set up a gyrating or "whorling" action in the cavity 27. The discharge from the small circular cavity 27 takes place through a very minute aperture 29 in the protruding portion of the tip 19, the approach to said aperture being tapered as shown at 29a to predetermined convergence of the flow and subsequent discharge at increased velocity through said aperture after the manner of a Venturi tube, and its exit—
15 as at 30—to facilitate tangential expansion of the efflux.

The vaporized liquid is expelled from the atomizer as hereinafter more fully explained, through the axial orifice 31 of a member 32 aligned with the nozzle N and screwed into a central opening 33 in the closed end of the casing shell 2. Here again I secure the advantage of Venturi action by tapering the approach of the orifice 31 as at 34, and of an expanding discharge by flaring the exit or outlet from said orifice as at 35. As a consequence of the opposed conical recessions in the contiguous faces of the tip 19 and the orificed member 32, a space 36 is formed
25 within the nozzle N, which space may be conveniently termed an *interacting* chamber, said chamber communicating circumferentially with the space 9, previously referred to, through a lateral interval 37, which
30 may be varied as required to suit exacting conditions of operation by adjustment of the shell 2 relative to the main body part 1 of the atomizer, as readily permitted by the threaded connection at 3.
35 As a means to enable regulation of the flow of the liquid to be vaporized, as well as that of the atomizing medium, I interpose in the pipe lines 7 and 8, hand valves 38 and 39 respectively. Also, if desired, gauges 40 and 41 may be employed, in connection with the valves 38 and 39, for convenience in maintaining the desired working pressures of the two fluids.

In operation of the device, the liquid conducted to the annular space 26 within the nozzle N by way of the passage 23 through the body member 1 and branch ducts 24 of the core piece 15, is gyrated in a clock-wise direction as it enters the circular cavity 27
50 within the tip 19 through the tangentially-disposed channels 28. The gyration or whorling thus induced is abruptly attenuated as it advances through the tapered approach 29a to the minute aperture 29 and is, accordingly, expelled through the latter at a very highly accelerated velocity, the efflux taking the form of a very fine tangentially flying jet under freedom of expansion allowed by the external flare 30 of said aperture.
55 The compressed atomizing medium ad-

mitted at the same time through the passage 13, first enters the space 10 and from thence passes through the inclined circumferential channels 11 en route to the space 9, being thus conducted into the latter in a gyrating or swirling condition. The gyrating or swirling flow, as it advances in the space 9, is caused to contract in passing through the lateral interval 37, and thus enters the chamber 36 at an increased speed of travel—and as a converging stream—to meet the tangentially expanding discharge of fluid projected through the nozzle aperture 29. Due to the interaction between the two fluid streams, the liquid jet is effectively broken up or atomized within the chamber 36, the interaction being—as a matter of fact—intensified by the Venturi effect of the constricted orifice 31 in the outlet member 32, so that a highly vaporized discharge issues from the atomizer flaring outlet 35. With the pressures properly regulated under control of the valves 38 and 39 and with the aid of the gauges 40 and 41, it will be apparent that very dense or highly viscous fluids may be atomized as readily as those of lower specific gravity. Although applicable to innumerable uses in practice, I again point out that my improved atomizer is particularly efficient in connection with the vaporization of hydro-carbons of the heavier varieties employed in oil burning systems, and good results are obtainable in this special application with pressure varying between the limits of ten and three hundred pounds in the oil delivery, and between like limits in the delivery of the atomizing medium, the exact pressures being determined entirely by the consistency of the liquid.

Having thus described my invention, I claim:

1. An atomizer embodying members providing opposed concavities constituting an interacting chamber, means serving as individual conduits for the supply of pressure-delivered liquid and an atomizing medium concurrently into said chamber with tangential and radially inward flow respectively, one of said conduits having a constricted orifice adapted to discharge the liquid at accelerated velocity, and the other of said conduits being adjustable to control the radially-inward flow of the atomizing medium into said chamber whereby the liquid is thoroughly vaporized and discharges as a tangentially-expanding combustible mist from the atomizer.

2. An atomizer embodying opposingly concaved members jointly affording an interacting chamber with constricted axial entry and discharge orifices, said members being spaced to provide a peripheral inlet to said chamber, one of said members constituting the tip of a co-axial internal nozzle including means for establishing in the entry orifice a

- comparatively fine rotating stream of liquid which upon issuing from such orifice into the interacting chamber expands tangentially of said orifice outwardly towards said peripheral inlet, and means with angularly-pitched channels to establish a swirling stream of compressed atomizing medium moving inwardly through the peripheral inlet towards the axis of said chamber to break up the liquid flow and effect a tangentially-expanding vaporized discharge from the atomizer discharge orifice. 5
3. An atomizer embodying opposedly-flared members jointly forming an interacting chamber with constricted axial entry and discharge orifices, said members being spaced to provide a peripheral inlet to said chamber, one of said members forming the tip of an internally-located nozzle having channels for establishing in the entry orifice a comparatively fine rotating stream of liquid which upon issuing therefrom into the interacting chamber expands tangentially to said orifice outwardly towards the peripheral inlet, 10 means including angularly-pitched channels to establish a swirling stream of compressed atomizing medium moving inwardly through the peripheral inlet towards the axis of the interacting chamber to break up the liquid flow and effect a tangentially-expanding vaporized discharge from the chamber discharge orifice aforesaid. 15
4. An atomizer embodying opposedly-flared members jointly forming an interacting chamber with constricted axial entry and discharge orifices, said members being spaced to provide a peripheral inlet to said chamber, one of said members constituting the tip of an internally-located nozzle with the orifice 20 therein serving as a minute Venturi discharge from a communicating co-axial circular hollow approached by tangentially-disposed channels, said channels establishing in the entry orifice a comparatively fine rotating stream of liquid for outward expansion into the chamber aforesaid as a comparatively fine tangentially-directed stream, and means to establish a swirling stream of concurrently-delivered compressed atomizing medium 25 moving inwardly through the peripheral inlet towards the axis of the interacting chamber to break up the liquid stream and effect a tangentially-expanding emission of vapor from the chamber discharge orifice aforesaid. 30
5. An atomizer embodying opposed conically-flared members jointly forming an interacting chamber with constricted axial entry and discharge orifices, said members being spaced to provide a peripheral inlet to said chamber, one of said members constituting the tip of an internally-located nozzle adapted to inject a fine rotating flow of liquid into the interacting chamber, means defining an annular space about the nozzle that 35
- communicates laterally into the inlet of the interacting chamber, said space being approached by a series of angularly-pitched channels in a circumferential enlargement of the nozzle, whereby compressed atomizing medium is swirled in the course of its delivery to the peripheral inlet of the interacting chamber to break up the flow of liquid and effect a tangentially-expanding discharge of atomized vapor from the constricted chamber discharge orifice aforesaid. 40
6. An atomizer embodying opposed conically-flared members jointly forming an interacting chamber with constricted axial entry and discharge orifices, said members being spaced to provide a peripheral inlet to said chamber, one of said members constituting the tip of an internally-located nozzle and having tangentially-disposed channels establishing in the entry orifice a comparatively fine rotating flow of liquid into the interacting chamber, means providing an annular passage surrounding the nozzle which communicates laterally into the inlet of the interacting chamber, said means being adjustable to vary the radially inward flow of concurrently-delivered compressed atomizing medium for transverse intersecting flow across the tangentially-expanding liquid in the interacting chamber and thereby effectively break it up before emission through the constricted discharge orifice aforesaid. 45
7. An atomizer embodying inner and outer reversely-flared components jointly forming an interacting chamber having constricted axial liquid-entry and vapor-discharge orifices, said components being spaced to provide an intervening peripheral inlet for atomizer-medium; said inner component constituting the tip of an internally-located nozzle having tangential channels adapted to establish a comparatively fine rotating supply of liquid to the entry orifice and its tangential expansion into the interacting chamber; a casing surrounding the nozzle setting apart an annular passage for concurrent supply of the compressed atomizer-medium to the peripheral inlet and its transverse radially-inward flow across the interacting chamber; and means permitting adjustment of said casing to vary the flow-velocity of the atomizer-medium into the interacting chamber and adjunctively to regulate the vapor density emitted from the atomizer discharge orifice aforesaid. 50
- In testimony whereof, I have hereunto signed my name at Philadelphia, Pennsylvania, this 13th day of February, 1925.
